CLAIM

The ornamental design for an aerosol generating device, as
shown and described.

DESCRIPTION

FIG. 1 is a front, top, and left side perspective view of an
aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front and top perspective view thereof; and,

FIG. 9 is a front and bottom perspective view thereof.
